UNITED STATES PATENT OFFICE.

OLIVER M. EDWARDS, OF SYRACUSE, NEW YORK.

TRAP-DOOR LOCK FOR RAILWAY-CARS AND SIMILAR STRUCTURES.

1,113,547.

Specification of Letters Patent.

Patented Oct. 13, 1914.

Application filed November 11, 1910. Serial No. 591,776.

To all whom it may concern:

Be it known that I, OLIVER M. EDWARDS, a citizen of the United States, residing at Syracuse, county of Onondaga, State of New York, have invented a certain new and useful Improvement in Trap-Door Locks for Railway-Cars and Similar Structures, of which the following is a full, clear, and exact description, reference being had 5 to the drawings accompanying the same.

This invention relates generally to "trap doors" for platforms of railway cars and locks for securing the same in the closed position and more particularly to "trap doors" provided with a spring or springs 15 adapted to aid in opening the same and locks for use with such doors.

One of its objects is to provide this class of "trap doors" with simple and efficient 20 locking means in which the door engaging portion or bolt is exposed to view so that the person in charge or others desiring to use the platform can tell at a glance whether or not the door is securely locked in place.

Another object is to provide this class of "trap doors" with locking means having 25 bolts or engaging parts which are simple and strong and engage with the top surface of the door when such door moves into the fully closed position thus exposing such locking bolt or engaging part to the eye of the person in charge or others desiring to use the platform.

Other objects will be apparent from the 30 descriptions hereinafter given and from the claims annexed hereunto.

With these and other objects in view the invention consists in the construction, parts or devices and the combinations or arrangements of the same to be hereinafter more 35 fully described and particularly pointed out in the claims hereunto annexed forming a part of this specification.

In practice, it has been found that locks 40 many times used to hold or lock trap-doors in position, when such doors are closed, do not securely hold or lock them in that position for the reason that the bolts or engaging portions of such locks do not fully move 45 into the locking position or become so worn that the bolts work back against the force of their springs, thereby releasing the door from their holding action. This permits the springs, many times applied to trap-doors, 50 to more or less lift the doors into the open position and thereby permit of passengers 55

or others stepping into the openings thus formed and injuring themselves.

Locks in common use on trap-doors provided with springs to aid in opening the 60 same have their bolts or engaging parts arranged below the top surface of the door and platform and out of sight of those desiring to use the vestibule platforms and the person in charge has no way of observing whether such bolts are in the fully 65 locked position or not, and is, therefore uninformed as to the actual condition of the lock. It is a well known fact that the twisting action of railway cars in passing over 70 uneven tracks or around curves places great strains upon the locks used for holding trap-doors in the closed position. Such twisting action tends to distort the relations of the 75 doors to the openings in the platforms in which they are hung and this very often interferes with operation of the locks and the movement of the bolts thereof into the fully locked position. These twisting actions many times cause the bolts of the locks to 80 gradually move into the unlocked position, moving a little at a time, out of locking or holding position.

Figure 1 illustrates in plan view one embodiment of my invention, a portion of a 85 car, vestibule and vestibule door being shown in cross section. Fig. 2 illustrates in side elevation and also partly in vertical transverse section the trap door mounted in the platform and in the closed position, the 90 door, platform and the mounting of the locking means being shown as on line 2-2 of Fig. 1. Fig. 3 shows on an enlarged scale a portion of the mounting for the locking bolt and the bolt itself, the latter being 95 in cross section on line 2-2 of Fig. 1. Fig. 4 is a view on an enlarged scale similar to Fig. 2 of the modified form of locking means, the trap door being broken away. Fig. 5 is a plan view of another form of 100 locking bolt. Fig. 6 shows in side elevation and in vertical section a modified form of the construction seen in Figs. 1 to 3, inclusive. Fig. 7 shows in plan view a portion of a trap door and platform with the locking means in full view, a portion of the casing and bolt being broken away to better illustrate the construction seen in Fig. 6. Fig. 8 shows in side elevation the locking bolt and casing as they appear in looking 110 in the direction of the arrow seen on that figure of the drawings.

Like letters of reference, wherever they occur indicate corresponding parts of the several figures of the drawings.

In the several figures of the drawings A 5 represents the platform and the portion of the car shown in which the trap-door B is hinged by any means and in any manner desired. The lock C is preferably arranged as shown being mounted on the platform adjacent to the body of the car so as to be out 10 of the way of those desiring to use the platform and trap-door, either when open or closed and yet be within convenient reach of the person in charge who is to open and close such door.

The lock C is preferably provided with a rotative part or bolt c preferably in eccentric form which is provided with a suitably beveled face so that whichever way the bolt 20 is pivotally mounted on the platform adjacent to the door opening, the door in closing will engage with such face and more or less rotate the bolt and move it out of locking position to permit the door to fully close. This bolt or part c of the lock C is 25 preferably mounted in position to be moved into the unlocked position by the turning of a shaft, as D, which shaft is mounted on the platform in a vertical position, as shown, 30 so as to turn in its mountings and permit the bolt, as c, to rotate or move sufficiently to lock or unlock the door. This bolt, as c, and the shaft, as D, are preferably so arranged relatively to the door and platform 35 that the entire bolt, as c, passes over the door in full sight of the person in charge, thus better enabling one to determine at a glance whether or not such bolt is in position to properly hold the door closed. As 40 shown a spring, as d, is arranged in such a manner that its stress always tends to move the shaft D and bolt or part c into the locking position. The stress of this spring is preferably such that it will under ordinary 45 circumstances keep the bolt, as c, in position to hold or lock the door B in the opening in the platform, when once such door is brought into place to close such opening.

As shown in Fig. 3 the spring, as d, is 50 arranged in a recess in the part, as c, one end of such spring being connected with the platform A and the other end with the part or bolt, as c, of the lock C. A handle, as H, is attached to the shaft D in a convenient 55 position to be grasped by the hand of the person in charge or he who desires to unlock the door.

In Fig. 4 the shape of the locking bolt c is somewhat different from that of the corresponding bolt in Figs. 1 to 3, but it operates in substantially the same manner as that bolt does. The bolt c seen in Fig. 5 is modified both in shape of its coacting face and the position in which it is mounted relatively to the door with which it coacts in

the closing of the same. When the bolt c is arranged as seen in Fig. 5, it is more easily moved out of locking position than when arranged as seen in Fig. 1, consequently the coacting face of the bolt may be shaped differently in Fig. 5 from what is necessary in the case of the locking bolt seen in Fig. 1.

In Figs. 6 to 8, inclusive, a modified construction is shown in which the bolt, as c, is permitted to move independently of the operating shaft, as D. As here shown this bolt as c, may be more or less rotated by the action of the door on the inclined or beveled surface of such bolt upon its closing without the shaft, with which the bolt is loosely connected, being moved. The bolt, as c, seen in Figs. 6 to 8, is pivotally mounted on a stud, as e, attached to the casing E of the locking means, as C. The shaft, as D, is provided with an arm, as e', the free end of which contacts with a portion of the bolt, as c, in such a manner as to move the bolt into the unlocked position when the shaft, as D, is turned in one direction, but such bolt is not moved in the opposite direction by turning such shaft. The bolt, as c, is moved into the locking position by the stress of the spring, as e², which keeps the bolt, as c, in contact with the free end of the arm, as e', mounted on the shaft, as D, when such bolt is free from strain and the spring, as e², controls its movement into the locking position. If, for any reason the bolt, as c, is held against moving into the locking position or following the return movement of the shaft, as D, the movement of such shaft is not interfered with and it can be moved into its normal position by the hand of the operator or otherwise without in any way affecting the bolt, as c. If it be desired to have the handle, as H, extend a greater distance from the shaft, as D, than shown, it can be pivotally connected with the shaft in any well known manner now used for so connecting handle portions to shafts, so that when not in use such handle portion is moved at its free end into position more or less parallel with the shaft to which it is attached.

The locking bolt, as c, as seen in Figs. 1 to 5, inclusive, is arranged wholly above the surface of the platform and door and it is also wholly exposed to view. The spring, as d, automatically returns the shaft D and its fixedly attached locking bolt to the position where the bolt can engage with the upper surface of the door, when in the closed position. In Figs. 6 to 8, the corresponding spring also automatically returns the shaft D to the position where it can be actuated to move the bolt out of locking position. As shown the shaft, as D, is extended down below the platform and is preferably provided with a handle, as H', by which such shaft may be partially rotated from underneath the car and the door unlocked so as to

be opened from the underside of the platform instead of from the upper surface thereof. This many times is advantageous, as for instance, when there is no one in the 5 car or vestibule.

In each of the constructions here shown the locking or holding part or bolt is pivotally connected to the platform with its axial line at right angles to the surface of the 10 door when in the closed position, this being the preferred manner of mounting the bolt or locking part to engage with the door and hold it in the closed position, but if desired such locking part or bolt may be otherwise 15 pivotally mounted to engage with the door, such bolt being suitably formed with the door to move it out of the locking position as such door is being closed.

What is herein shown and described will 20 naturally suggest to those skilled in the art other specific forms of locking means for trap doors of the class herein referred to which are arranged for the locking bolt or bolts to engage with the door in plain sight 25 of the person or persons using the platform in which the doors are placed and modifications of that which is herein shown and described which, while varying in form or details of construction of arrangement will 30 have substantially the same method or mode of operation in accomplishing essentially the same work as is accomplished by that herein set forth, hence, I do not desire to limit my invention to the specific forms, constructions 35 or arrangements of parts or devices herein shown and described, but desire to include all forms, constructions and arrangements that are within the spirit of my invention.

What I claim as new is:—

40 1. In a car platform the combination, substantially as set forth, of a trap door mounted therein, locking means provided with a pivotally mounted locking bolt having a face adapted to coact with the door when closing to move it out of locking position and arranged relatively to the door and platform to be exposed to view when in position to lock the door in the platform, and operating means for actuating such bolt out of locking 45 position to release the door.

50 2. In a car platform the combination, substantially as set forth, of a trap door mounted therein, locking means provided with a pivotally mounted locking bolt arranged 55 above the surface of the platform and door

in plain sight of the operator having a face which coacts with the door in closing the same, and operating means adapted to move such bolt into position to release the door.

3. In a car platform the combination, substantially as set forth, of a trap door mounted therein, locking means provided with a pivotally mounted locking bolt arranged to engage with the upper surface of the door and movable in planes substantially parallel with such surface and having a face adapted to coact with the door in closing the same, and operating means adapted to move such bolt into position to release the door. 60

4. In a car platform the combination, substantially as set forth, of a trap door mounted therein, a pivotally mounted locking bolt arranged on its pivot at an angle to the platform and to engage with the upper surface of the door for locking the same in the 70 platform, having an eccentric face to coact with the door in closing or moving the bolt out of locking position, and operating means for releasing the door from the locking bolt. 75

5. In a car platform, the combination of a trap door mounted therein, locking means provided with a pivotally mounted locking bolt arranged with its axial line at an angle to the plane of the platform, and having a 80 cam face normally arranged in the path of the door as the door approaches the limit of its closed position, such cam face extending spirally around the axis of the locking bolt, and operating means connected to the bolt and arranged to withdraw the bolt out of operative position, substantially as and for the purpose described. 85

6. In a car platform, the combination of a trap door mounted therein, locking means, 95 and operating means for moving the locking means out of operative position, the operating means comprising a rock shaft arranged at an angle to the plane of the platform, a bolt mounted on the rock shaft and a spring 100 encircling the shaft and acting on the bolt for moving the bolt into operative position and permitting the latching action thereof, substantially as and for the purpose described.
